United States Patent

Des. 236,435
Patented Aug. 26, 1975

236,435

PREFORM FOR A FOOD JAR OR THE LIKE

Bryant Edwards, Clarendon Hills, Ill., assignor to Illinois Tool Works Inc., Chicago, Ill.

Filed July 5, 1973, Ser. No. 376,639

Term of patent 14 years

Int. Cl. D3—99

U.S. Cl. D9—171

FIG. 1 is a side elevational view of a preform for a food jar or the like showing my new design;

FIG. 2 is a top plan view;

FIG. 3 is a bottom plan view;

FIG. 4 is an enlarged fragmentary cross sectional view taken on the line 4—4 of FIG. 2; and

FIG. 5 is a fragmentary cross sectional view on a still larger scale taken on the line 5—5 of FIG. 2.

I claim:

The ornamental design for a preform for a food jar or the like, as shown.
